CLAIM

The ornamental design for a laptop computer, as shown and described.

DESCRIPTION

1.1 is a front view of a laptop computer showing the new design;

1.2 is a back view thereof;

1.3 is a left view thereof;

1.4 is a right view thereof;

1.5 is a top view thereof;

1.6 is a bottom view thereof;

1.7 is a perspective view thereof; and

1.8 is a perspective view thereof, showing the laptop computer in an opened state.

The broken lines shown in the drawings illustrate portions of the laptop computer that form no part of the claimed design.

(Continued)

The dot-dash broken lines illustrate the boundary of the claimed design and form no part thereof.

1 Claim, 8 Drawing Sheets
